UNITED STATES PATENT OFFICE.

JOSEPH BABST, OF NEW YORK, N. Y., ASSIGNOR TO WILLIAM SCHIMPER & CO., OF HOBOKEN, NEW JERSEY.

PICTURE-SUPPORT.

SPECIFICATION forming part of Letters Patent No. 662,140, dated November 20, 1900.

Application filed August 11, 1900. Serial No. 26,564. (No model.)

To all whom it may concern:

Be it known that I, JOSEPH BABST, a citizen of the United States, and a resident of the borough of Manhattan, in the city and State 5 of New York, have invented a new and useful Improvement in Easel-Back Supports, of which the following is a specification.

My invention relates to an improvement in easel-back supports, and has more particularly for its object to provide means for hinging the support to the back, comprising a hinged member having a transverse socket therein for receiving the inwardly-turned ends of the loop-support and stops carried by 10 the hinge member for retaining the ends of the support within the hinge member in whatever position the support is swung.

A further object is to provide means which will serve the double function of retaining the 15 inwardly-turned ends of the loop-support within the hinge member and also as stops to limit the outward swinging movements of the support.

A practical embodiment of my invention is 20 represented in the accompanying drawings, in which—

Figure 1 represents in perspective a back view of an easel-back and its support attached thereto. Fig. 2 is an enlarged face view of the 25 blank which forms the hinge member of the support. Fig. 3 is a face view of the hinge member after the transverse socket and the end pockets have been formed therein. Fig. 4 is a face view of the hinge member after the 30 transverse socket and the end pockets have been formed and the securing-tongues have been bent into position to secure the hinge member to the easel-back. Fig. 5 is a partial back view of the easel-back and its support, 35 showing the manner of mounting the support in the hinge member; and Fig. 6 is a transverse vertical section in the plane of the line 6 6 of Fig. 5.

The easel-back is denoted by A, and it may 40 form the back of a picture, mirror, or other similar article, as may be desired.

The support for the easel-back is denoted by B, and it consists of a wire bent into looped form, with its ends brought into proximity at 45 the top of the support, the wire at the bottom of the support being bent so as to engage the surface upon which the easel is resting at two

points, as shown at b b'. The meeting ends of the wire which forms the supporting-leg are denoted by b² b³, and they are bent toward 55 each other, as shown.

The hinge member, which connects the support B to the easel-back A, is made of sheet metal or other suitable material, and it comprises a body portion C, having upper and 60 lower tongues c c' projecting therefrom, and also provided with laterally-extended wings c² c³ partially severed from the body portion C. A transverse socket c⁴ is formed in the body portion of the hinge member, and the wings 65 c² c³ are bent outwardly and then inwardly to form pockets at the opposite ends of the socket c⁴. The outwardly-bent portions of the wings serve to limit the swinging movements of the support B in an outward direction and 70 the inwardly-bent portions of the said wings serve to hold the two ends of the wire which forms the support B snugly in position within the socket c⁴, serving also as stops to prevent the outward spreading of the said 75 ends.

The support is connected to the easel-back in the following manner: The ends b² b³ of the wire which forms the support are inserted in the socket c⁴ in the hinge member. The 80 hinge member is then fastened securely to the easel-back by passing the tongues c c' therethrough and then turning the tongues toward each other, as shown clearly in Fig. 6. If desired, a strengthening-plate D may 85 be placed along the front of the easel-back A at the point where the tongues are passed therethrough for strengthening the easel-back at this point and serving to more securely retain the hinge member in position. 90

It is evident that changes might be resorted to in the form and arrangement of the several parts without departing from the spirit and scope of my invention. Hence I do not wish to limit myself strictly to the structure here- 95 in set forth; but

What I claim is—

1. The combination with an easel-back and a loop-support therefor having its ends turned inwardly toward each other, of means for 100 hinging the support to the back comprising a hinge member having a transverse socket therein for receiving the inwardly-turned ends of the support and stops carried by the

hinge member retaining the ends of the support within the hinge member in whatever position the support is swung, substantially as set forth.

- 5 2. The combination with an easel-back and a loop-support therefor having its ends turned inwardly toward each other, of means for hinging the loop-support to the back comprising a hinge member having a transverse socket 10 therein for receiving the inwardly-turned ends of the support, the said hinge member also being provided with wings which are bent to form pockets for retaining the ends of the loop-support in position within the hinge 15 member in whatever position the support is swung, substantially as set forth.
3. The combination with an easel-back and a loop-support having its ends turned inwardly toward each other, of means for hinging the loop-support to the back comprising 20 a hinge member having a transverse socket therein for receiving the inwardly-turned ends of the loop-support, the said hinge member being provided with wings, which are bent to form pockets which serve the double 25 function of retaining the inwardly-turned

ends of the support within the hinge member and also as stops to limit the outward swinging movement of the support, substantially as set forth.

4. The combination with an easel-back and a loop-support having its ends turned inwardly toward each other, of means for hinging the support to the back comprising a hinge member having a transverse socket 35 therein for receiving the inwardly-turned ends of the loop-support, the said hinge member being further provided with wings bent to form sockets for retaining the ends of the loop-support within the hinge member in 40 whatever position the support is swung, and tongues arranged to clamp the hinge member to the easel-back, substantially as set forth.

In testimony that I claim the foregoing as my invention I have signed my name, in presence of two witnesses, this 17th day of July, 1900.

JOSEPH BABST.
